Robert J. Nicholson,
By G. L. Clegg, Attorney

UNITED STATES PATENT OFFICE.

ROBERT J. NICHOLSON, OF CHICAGO, ILLINOIS.

BOOKBINDER.

1,063,375.

Specification of Letters Patent.

Patented June 3, 1913.

Application filed February 16, 1912. Serial No. 678,039.

To all whom it may concern:

Be it known that I, ROBERT J. NICHOLSON, a citizen of the United States, residing at Chicago, in the county of Cook and State of Illinois, have invented a certain new and useful Improvement in Bookbinders, of which the following is a full, clear, concise, and exact description, reference being had to the accompanying drawings, forming a part 10 of this specification.

My invention relates to improvements in book-binders or holders, and has for its object the provision of novel and effective mechanism whereby fillers or books may be 15 readily placed within or removed from their covers or back elements. A construction devised for the purpose is also disclosed in my application Serial No. 367,938, filed April 13, 1907.

20 The nature and advantages of the construction of my present invention will be fully understood from the following description of the preferred embodiment of the invention, shown in the accompanying drawing, in which—

Figure 1 is a perspective view of a part of the book structure; Fig. 2 is a plan view of a part of the structure shown in Fig. 1; Fig. 3 is a view of the structure shown in 30 Fig. 2 with one of the parts in another adjustment; Fig. 4 is a sectional view on line 4-4 of Fig. 2; and Fig. 5 is a sectional view on line 5-5 of Fig. 3.

Like parts are indicated by similar characters of reference throughout the different figures.

The back element *a* preferably constitutes a separable cover designed to engage the backs of books or fillers, such as pamphlets, 40 magazines, etc., a book *b* being shown provided with such a covering. In order that this back element *a* may engage the back of the book, it is preferably provided with upwardly extending arms *c* *c'*, that are secured to the back element in any suitable way. In the preferred embodiment of the invention, these upwardly extending arms 45 constitute the angular ends of a metal strip *d*, which is caused to form a part of the back 50 element *a*. The arms *c* *c'* are provided with openings therein for the reception of a bar *e*, preferably of metal and desirably oblong in cross-section to enable it to be held from rotating, turning, or shifting, by the two 55 portions of the book or filler between which the bar is disposed, for a purpose which will

appear. That end of the bar which engages the arm *c* desirably passes through an opening therein and is so related thereto that it may, while maintaining its engagement with the arm *c*, be swung sufficiently clear of the cover, to enable a book to be placed within, or removed from, the cover. In the preferred embodiment of the invention, this end of the bar is desirably wedge-shaped, so as 60 to limit its outward projection, and is bent up at its extreme end to constitute a fastening device to prevent the withdrawal of this end of the bar. I do not wish to be limited, however, to the manner in which the arm 65 *c* is associated with the bar *e* in carrying out the object of my invention. The arm *c'* is designed to have separable engagement with the remaining or second end of the bar, the entire arrangement being such that 70 the bar may be turned or rotated, partially or completely, the bar in one of its positions being adapted to have its said second end disengaged from the arm *c'* and in an alternative position being held by the arm *c'*. 75 The book, itself, serves to hold the bar in its latter position.

In carrying out the object of my invention, the arm *c'* is provided with an opening *c*² having a restricted outlet *c*³ lying in the 80 plane that the major portion of the bar occupies when being normally held by the book. The portion, or second end of the bar *e*, that is adjacent to the arm *c'* is bent or twisted to occupy a plane that is trans- 85 verse or angular with respect to the plane occupied by the balance of the bar, whereby said second end of the bar may not be withdrawn through the restricted outlet *c*³ when the book is in normal relation with the 90 cover or back element within which it is disposed, the arm *c'* then surrounding the twisted end of the bar.

When it is desired to remove the cover from the book, the book is opened at the 100 place where the bar is located and then laid flat, whereafter the bar is given a quarter turn to bring its second or twisted end into the same plane with the restricted outlet *c*³ to permit of the elevation of the bar, so that 105 the book may be inserted within or withdrawn from the back element or cover.

I believe it to be broadly new with me to provide a construction wherein the book is adapted to hold the bar so that the bar is 110 held in engagement with the back element in order to hold the book in place, and while I

prefer to employ a construction by which the book holds the bar from material turning movement for the purpose stated, I do not wish to be limited to such construction in all 5 embodiments of my invention.

While I have herein shown and particularly described the preferred embodiment of my invention, I do not wish to be limited to the precise construction shown, as changes 10 may readily be made without departing from the spirit of my invention.

Having thus described my invention, I claim as new and desire to secure by Letters Patent the following:—

15 1. A device for holding books, including a back element carrying an arm provided with an opening having a restricted outlet, a bar adapted to be engaged at its ends with the back element and adapted for insertion between the leaves of the book to be held and having a fastening portion adapted for passage through said restricted outlet and adapted to be received by the opening in said arm, said bar being rotatable or turnable about an axis extending longitudinally of the back element, whereby the part thereof received by the opening in said arm may be brought into position, to be passed through the outlet from said opening or 20 may be brought into position to have its passage through said outlet prevented, the bar having unequal cross-sectional dimensions, which permit it to be held by the book when in normal relation with the bar, to prevent the bar from being moved to that position in which the fastening portion may be moved through the outlet provided for the opening in the arm.

2. A device for holding books, including 40 a back element carrying an arm provided with an opening having a restricted outlet, a bar adapted to be engaged at its ends with the back element and adapted for insertion between the leaves of the book to be held, the portion thereof received between the leaves of the book having unequal cross-sectional dimensions, in order that the book that is being held may hold the bar in relation to the book, the end portion of the bar adjacent to said arm also having unequal cross-sectional dimensions, the said two portions of the bar lying in different planes, whereby the book may hold the bar to prevent the end portion of the bar from being removed 50 through said outlet, said bar being rotatable or turnable about an axis extending longitudinally of the back element when the book is opened, in order to permit said end portion to be moved through said outlet.

60 3. A device for holding books, including a back element carrying one part of a fastening device and a bar adapted to be engaged at its ends with the back element and adapted for insertion between the leaves of the book to be held, and carrying a fastening 65

part complementary to the aforesaid part of the fastening device, said bar being rotatable or turnable about an axis extending longitudinally of the back element, said parts of the fastening devices being separable 70 when the bar is rotated to occupy one position, and being inseparable when occupying an alternative position, the bar having unequal cross-sectional dimensions, which permit it to be held by the book when in normal relation with the bar, to prevent the bar from being moved to that position in which the aforesaid complementary parts of the fastening device may be separated.

4. A device for holding books, including a 80 back element carrying one part of a fastening device and a bar adapted to be engaged at its ends with the back element and adapted for insertion between the leaves of the book to be held, and carrying a fastening 85 part complementary to the aforesaid part of the fastening device, said bar being rotatable or turnable about an axis extending longitudinally of the back element, said parts of the fastening devices being separable when 90 the bar is rotated to occupy one position and being inseparable when occupying an alternative position.

5. A device for holding books, including a 95 back element carrying an arm provided with an opening having a restricted outlet, a bar adapted to be engaged at its ends with the back element and rotatable about an axis extending longitudinally of the back element, and adapted for insertion between the 100 leaves of the book to be held, and having a fastening portion adapted, when the bar is rotated to one position, for passage through said restricted outlet, and, when rotated to another position, adapted to be received by 105 the opening in said arm.

6. A device for holding books, including a 110 back element carrying an arm provided with an opening having a restricted outlet, and a bar in engagement at its ends with the back element and having at its end a fastening portion rotatable about an axis extending longitudinally of the back element, said fastening portion, when rotated to one position, being adapted for passage through said outlet, and, when rotated to an alternative position, being adapted to be held within the opening in said arm.

7. A device for holding books, including a 120 back element carrying an arm provided with an opening having a restricted outlet, a bar adapted for insertion between the leaves of the book to be held and having a fastening portion adapted for passage through said restricted outlet and adapted to be received 125 by the opening in said arm, said bar being rotatable or turnable about an axis extending longitudinally of the back element, whereby the part thereof received by the opening in said arm may be brought into 130

position, to be passed through the outlet from said opening or may be brought into position to have its passage through said outlet prevented, the bar having unequal cross-sectional dimensions, which permit it to be held by the book when in normal relation with the bar, to prevent the bar from being moved to that position in which the fastening portion may be moved through the outlet provided for the opening in the arm.

8. A device for holding books, including a back element carrying an arm provided with an opening having a restricted outlet, a bar adapted for insertion between the leaves of the book to be held, the portion thereof received between the leaves of the book having unequal cross-sectional dimensions, in order that the book that is being held may hold the bar in relation to the book, the end portion of the bar adjacent to said arm also having unequal cross-sectional dimensions, the said two portions of the bar lying in different planes, whereby the book may hold the bar to prevent the end portion of the bar from being removed through said outlet, said bar being rotatable or turnable about an axis extending longitudinally of the back element when the book is opened, in order to permit said end portion to be moved through said outlet.

9. A device for holding books, including a back element carrying one part of a fastening device and a bar adapted for insertion between the leaves of the book to be held, carrying a fastening part complementary to the aforesaid part of the fastening device, said bar being rotatable or turnable about an axis extending longitudinally of the back element, said parts of the fastening devices being separable when the bar is rotated to occupy one position and being inseparable when occupying an alternative position, the bar having unequal cross-sectional dimensions, which permit it to be held by the book when in normal relation with the bar, to prevent the bar from being moved

to that position in which the aforesaid complementary parts of the fastening device may be separated.

10. A device for holding books including a back element carrying one part of a fastening device and a bar adapted for insertion between the leaves of the book to be held, carrying a fastening part complementary to the aforesaid part of the fastening device, said bar being rotatable or turnable about an axis extending longitudinally of the back element, said parts of the fastening devices being separable when the bar is rotated to occupy one position and being inseparable when occupying an alternative position.

11. A device for holding books, including a back element carrying an arm provided with an opening having a restricted outlet, a bar rotatable about an axis extending longitudinally of the back element, adapted for insertion between the leaves of the book to be held, and having a fastening portion adapted, when the bar is rotated to one position, for passage through said restricted outlet, and, when rotated to another position, adapted to be received by the opening in said arm.

12. A device for holding books, including a back element carrying an arm provided with an opening having a restricted outlet, and a bar having at its end, a fastening portion rotatable about an axis extending longitudinally of the back element, said fastening portion, when rotated to one position, being adapted for passage through said outlet, and, when rotated to an alternative position, being adapted to be held within the opening in said arm.

In witness whereof, I hereunto subscribe my name this 9th day of August A. D., 1909.

ROBERT J. NICHOLSON.
